UNITED STATES PATENT OFFICE.

EDGAR TAYLOR AND ANDREW B. COLLINS, OF OZARK, ARKANSAS; SAID COLLINS AS SIGNOR TO SAID TAYLOR.

INCLINOMETER.

Application filed December 16, 1922. Serial No. 607,327.

To all whom it may concern:

Be it known that we, EDGAR TAYLOR and ANDREW B. COLLINS, citizens of the United States, residing at Ozark, in the county of 5 Franklin and State of Arkansas, have invented certain new and useful Improvements in Inclinometers, of which the following is a specification.

This invention relates to measuring instruments and has special reference to an inclinometer.

More particularly the invention relates to an inclinometer attachment peculiarly adapted for use in connection with any 15 straight edge or the like.

One important object of the invention is to improve the general construction of devices of this character wherein the level bubble employed may be shifted to various 20 angular positions with relation to the straight edge and there held by spring friction.

A third important object of the invention is to provide improved means for mounting 25 the movable level tube in such an instrument.

With the above and other objects in view as will be hereinafter apparent, the invention consists in general of certain novel de- 30 tails of construction and combinations of parts hereinafter fully described, illustrated in the accompanying drawings and specifically claimed.

In the accompanying drawings, like characters of reference indicate like parts in the several views, and:-

Figure 1 is a face view of an inclinometer constructed in accordance with this invention.

40 Figure 2 is a section on the line 2-2 of Figure 1.

Figure 3 is a section on the line 3-3 of Figure 1.

In carrying out this invention there is 45 provided a base 10 preferably of metal or the like and depending from this base are spaced flanges 11 and 12. The flange 12 is provided with a boss 13 wherethrough passes a clamping screw 14 having a knurled head

50 15 carried by this base, and preferably formed integral therewith, is a casing or box 16 of substantially cylindrical form and closed at the back as shown at 17. The front of this casing is provided with a rabbet 18 and on the face of this rabbet are

graduations 19 as best seen in Figure 1. Extending rearwardly from the back 17 is a boss 20 having a frusto-conical opening 21 which is surrounded by an annular channel 22. Through this frusto-conical opening 60 extends a frusto-conical stem 23 which projects rearwardly from a bubble tube container 24 holding the bubble tube 25, the center of the latter being exposed through a window opening 26. This bubble tube is 65 held in position by caps 27 at each end of the tube 24 and each of these caps is provided with an index or pointer 28 extended close to the graduations 19 so that the position of the bubble tube may be readily determined. On the end of the stem 23 is a knurled nut 29 which is secured thereon by means of a screw 30 and washer 31. Under this knurled head is located a spring 32, the 70 forward end of which is received in the annular recess 22.

Now it will be observed that by reason of the frusto conical fit of the stem 23 the latter is accurately centered, and that the spring 32 serves to hold this stem properly 80 in position while at the same time causing sufficient frictional engagement to prevent accidental shifting of the bubble tube 24 on its axis. Thus when the inclinometer is applied to a straight edge, as at S, and the 85 bubble tube properly set, the device may be handled without fear of changing the setting accidentally. Furthermore, it is obvious that by means of the knurled nut 29 the bubble tube may be readily turned, a slight pressure inward of this nut freeing the grip of the frusto-conical opening on the stem 23.

There has thus been provided a simple and efficient device of the kind described 90 and for the purpose specified.

It is obvious that minor changes may be made in the form and construction of the invention without departing from the material spirit thereof. It is not, therefore, 100 desired to confine the invention to the exact form herein shown and described but it is desired to include all such as properly come within the scope claimed.

Having thus described the invention what 105 is claimed as new, is:-

An inclinometer comprising a cylindrical casing having a closed back provided with a centrally disposed boss having an axially arranged frusto conical opening and an an- 110

nular channel opening rearwardly, concentric with and surrounding said opening; a bubble tube container in said casing, a bubble tube in said container, said container having a window through which said tube may be observed, a frusto conical stem carried by the tube container at the transverse center thereof, extending at right angles to said tube support and passing through the frusto conical opening, a head on said stem secured to and at the rear of said boss, a spring seated in said channel and bearing against the underside of said head for nor-

mally holding the tube support in an adjusted position in said casing, there being 15 graduations on the casing, and indicating members carried directly by the terminals of the tube container for cooperation with said graduations.

In testimony whereof we affix our signatures in presence of two witnesses.

EDGAR TAYLOR.
ANDREW B. COLLINS.
